Emery A. Shook,
INVENTOR

BY Victor J. Evans
ATTORNEY

Levi Hayes
WITNESS:

UNITED STATES PATENT OFFICE

EMERY A. SHOOK, OF CORNING, CALIFORNIA

WRENCH

Application filed October 27, 1930. Serial No. 491,541.

The object of this, my present invention, is the provision of a wrench which may be accurately adjusted to regulate the opening between the jaws thereof, which may be adjusted to an exact precision for use on square, hexagon or octagon nuts, which can be easily and readily applied to a nut or pipe by simply swinging the handles of the wrench toward or away from each other, and which also embodies the desirable features of simplicity in construction, cheapness in manufacture and thorough efficiency in actual use.

To the attainment of the foregoing the invention consists in the improvement herein-after described and definitely claimed.

In the drawing:

Figure 1 is a side elevation of the improvement.

Figure 2 is a top plan view thereof.

Figure 3 is a sectional view approximately on the line 3—3 of Figure 2.

Figure 4 is a transverse sectional view approximately on the line 4—4 of Figure 3.

Figure 5 is a similar sectional view approximately on the line 5—5 of Figure 3.

It will be noted as the description progresses that the improvement is in the nature of a combination tool, that is, the same is successfully employed as either a wrench or a pair of pliers. The stationary jaw 1 of the improvement may have its active face toothed or serrated and the same is formed with a right angularly disposed shank 2 that terminates in a curved handle 3. The shank 2, from a line with the active face of the jaw, is provided with an elongated substantially rectangular slot or opening 4 and with a transverse notch 5 that intersects the opening at the inner portion thereof. The notch is designed to receive therein a knurled nut 6 and this nut has a threaded engagement with a worm screw 6' that extends from one end of a follower member 7 that is guided in the slot 4. By reference to Figure 3 of the drawing it will be noted that the shank is provided with a longitudinal opening 8 that communicates with the notch 5 and which provides for the reception of the worm screw 6' therein.

The movable jaw of the wrench is indicated by the numeral 9. The jaw, at the por-

tion thereof which underlies the shank 2 is cut angularly to provide a shoulder 10 and from the inner wall of the shoulder the said jaw is formed with a reduced extension 11 that is arranged in lapping relation to one side of the shank 2. Preferably and as disclosed by the drawing the jaw 1 is widened beyond the side of the shank 2 against which the reduced portion 11 of the movable jaw 9 contacts. There is passed through the following block 7 and the part 11 of the movable jaw 9 a headed pivot 12 for the jaw 9. The head of the pivot bridges the slot 4 and holds the block 7 in the slot. The jaw 9, from its part 11 is formed with a reduced extension in the nature of a shank 13 which is also in lapping relation with respect to the shank 2 and which shank 13 merges into a handle 14 which is arched at an opposite curvature to that of the handle 3. By reference, especially to Figure 5 of the drawing, it will be noted that the inner face of the shank 11 may be brought into frictional contact with the periphery of the knurled nut 6 so that when the handle 14 is forced toward the handle 3 in the swinging of the handles toward each other, this contacting engagement between the shank and nut will turn the nut to advance the jaw 9 toward the jaw 1 for a minute adjustment of the jaws with respect to the article gripped therebetween and likewise the swinging of the handles 3 and 14 away from each other will cause the nut to be slightly turned in an opposite direction to bring the jaw 9 away from the jaw 1 and thus permit of the ready separation of the jaws from the engaged articles. The major adjustment between the jaws, however, is accomplished when the handles 3 and 14 are sufficiently spread to permit of the operator turning the nut 6. It is to be further noted that the nut 6 projects only beyond one of the sides of the shank 2.

While in the showing of the drawing the active faces of the jaws 9 and 1 are toothed or serrated it is obvious that the said faces of the jaws may be smooth and it is believed the foregoing description will fully and clearly set forth the simplicity of the construction and the advantages thereof to those skilled in the art so that further detailed description

will not be required. Obviously I do not wish to be restricted to the precise details herein shown and described and, therefore, hold myself entitled to make such changes therefrom as fairly fall within the scope of what I claim.

Having described the invention, I claim:

A wrench of the character described, comprising a stationary jaw having a shank 10 which merges into a handle and the said shank being provided with a rectangular slot that merges into a notch and with an opening that communicates with the notch, a block arranged in the slot and in contact with the 15 opposed longitudinal walls thereof, said block having a worm screw which is received in the opening, a nut which is round in plan and peripherally knurled received in the notch and engaging the worm, a movable jaw having a reduced portion arranged against 20 one side of the shank, and a headed pivot passing through the block and said reduced portion and the head of the pivot holding the block in the slot, a shank formed at the 25 reduced portion of the movable jaw and merging into a handle, and designed to frictionally engage with the knurled nut when the mentioned handles are swung and forced toward each other.

In testimony whereof I affix my signature.
